CLAIM

The ornamental design for a set of photo frames, as shown and described.

DESCRIPTION

FIG. 1 is a perspective view of a first photo frame of the set of photo frames showing my new design;
FIG. 2 is a perspective view thereof from another angle;
FIG. 3 is a left side elevational view thereof;
FIG. 4 is a right side elevational view thereof;
FIG. 5 is a rear elevational view thereof;
FIG. 6 is a front elevational view thereof;
FIG. 7 is a top plan view thereof;
FIG. 8 is a bottom plan view thereof;
FIG. 9 is a perspective view of a second photo frame of the set of photo frames showing my new design;
FIG. 10 is a perspective view thereof from another angle;
FIG. 11 is a left side elevational view thereof;
FIG. 12 is a right side elevational view thereof;
FIG. 13 is a rear elevational view thereof;
FIG. 14 is a front elevational view thereof;
FIG. 15 is a top plan view thereof;
FIG. 16 is a bottom plan view thereof;
FIG. 17 is a perspective view of a third photo frame of the set of photo frames showing my new design;
FIG. 18 is a perspective view thereof from another angle;
FIG. 19 is a left side elevational view thereof;
FIG. 20 is a right side elevational view thereof;
FIG. 21 is a rear elevational view thereof;
FIG. 22 is a front elevational view thereof;
FIG. 23 is a top plan view thereof;
FIG. 24 is a bottom plan view thereof;
FIG. 25 is a perspective view of a fourth photo frame of the set of photo frames showing my new design;
FIG. 26 is a perspective view thereof from another angle;
FIG. 27 is a left side elevational view thereof;
FIG. 28 is a right side elevational view thereof;
FIG. 29 is a rear elevational view thereof;
FIG. 30 is a front elevational view thereof;
FIG. 31 is a top plan view thereof;
FIG. 32 is a bottom plan view thereof; and,
FIG. 33 is a perspective view of the set of photo frames of my new design.
